UNITED STATES PATENT OFFICE.

JOHN D. RAYMOND, OF CHICAGO, ILLINOIS.

DESIGN FOR A LIGHTING-FIXTURE.

48,082.

Specification for Design.

Patented Nov. 2, 1915.

Application filed June 9, 1915. Serial No. 33,189. Term of patent 7 years.

To all whom it may concern:

Be it known that I, JOHN D. RAYMOND, a citizen of the United States, residing at Chicago, in the county of Cook and State of Illinois, have invented a new, original, and ornamental Design for Lighting-Fixtures, of which the following is a specification, reference being had to the accompanying drawing, forming a part thereof.

The drawing is a side elevation of a lighting fixture, showing my new design.

I claim:

The ornamental design for a lighting fixture, as shown.

JOHN D. RAYMOND.
